UNITED STATES PATENT OFFICE

1,967,473

ALLOCATOR FOR DUPLICATING STAMPS

George J. Helfrich, Cincinnati, Ohio

Application January 10, 1933, Serial No. 650,971

12 Claims. (Cl. 101—413)

My invention relates to a device for accurately locating the impression of a duplicating stamp, particularly of the stencil type, upon the card or sheet upon which such impression is to be made.

The present invention has for its chief object and is directed principally to extending the advantages attained by the allocator described and claimed in my copending application filed December 3, 1932, Serial No. 645,560; now Patent No. 1,949,864, and to facilitating and rendering even more accurate the operations therein described.

A further object of the present invention is to provide in connection with mechanism of the type described in my said application, means for so accurately gauging the location of an impression on a card or sheet that such stamp or a plurality of such stamps may be used for successive impressions, as in multi-color work.

20 Further objects of my invention will appear from the following detailed description thereof.

In the drawings:

Figure 1 is a plan view of a device constructed in accordance with this invention.

25 Figure 2 is a section on line 2—2 of Figure 1.

Figure 3 is a plan view of an auxiliary device for use with the allocator in accurately gauging and setting the mechanism.

Figure 4 is a section on line 4—4 of Figure 2.

30 Figure 5 is a view of a modification.

The numeral 1 indicates a bed plate, the same being provided with upwardly turned side flanges 2 and 3 and an upwardly turned rear flange 4. Secured to the side flanges 2 and 3 are plates 5—5 35 the ends of which are bent at right angles to provide front extensions 6—6 and rear extensions 7—7; the latter resting against and reinforcing the rear flange 4. Secured between each pair of the extensions 6 and 7 is a rod 8; the upper surface 40 of each of which may be calibrated as shown.

Slidably mounted in each of the rods 8 is a sleeve or collar 9, said collars serving as end supports for a transverse rod 10. The collars 9 are provided with pointers 11 which are adapted to read 45 on the calibrations of the rods 8. Set screws 12 thread into the collars 9 and secure the same in desired location on the rods 8, reference being had to the desired forward or rearward adjustment of the rod 10 with respect to the bed 1.

50 Slidably mounted on the rod 10 are sleeves or collars 13—13 to which are secured arms 14—14 carrying a plate 15 which is adapted to lie flat on the bed plate 1. Also secured to the collars 13 are spring arms 16—16, to the forward ends of which 55 a plate 17 is secured by soldering, welding or in

any other suitable manner. The plate 17 has a depending flange 18, and a short depending end flange 19. Secured on the plate 15 are pins 20 on which a heavy plate or platen 21 is mounted; said platen being of suitable size for the cards or sheets to be printed. The collars 13 being slideable on the rod 10, it will be observed that the plate 15 and with it the platen 21 may be moved laterally in any desired adjustment on the bed, set screws 22 being provided to secure such adjustment. The upper surface of the rod 10 is calibrated as shown, and a pointer 23 provided on one of the collars to read on said calibrations to facilitate such adjustments. Similarly forward and rearward motion of the rod 10 with respect to plate 1 being permitted by the sliding collars 9—9 on the rods 8—8, forward and rearward adjustments on the platen on the bed plate may be made.

Secured between the upper forward ends of the flanges 2 and 3 is a transverse plate 24 which is provided with a plurality of deep notches or slots 25. The plate 24 has downwardly extending end sections 26 between which a cylindrical rod 27 is secured either by soldering, welding or in any other suitable manner. The rod 27 thus secured extends from end to end of the plate 24, and is located just under the forward edge thereof so as to be accessible through the front portions of the slots 25.

Secured on the stamp 28 is a plate 29 which has outwardly extending lugs 30—30, the lower edges of same being provided with notches 31. The lugs 30—30 are adapted to enter a pair of slots 25, and the notches 31 of said lugs are adapted to fit over and ride upon the rod 27. Said lugs and notches 35 in connection with the rod 27 thus serve to allocate the stamp with respect to the platen 21 which has, of course, been attached to the bed over the pins 20, and also in relation to the slots 25 of the plate 24.

In order to achieve the ultimate in accuracy of adjustment of the platen with respect to the slots 25 in plate 24, and corresponding accuracy in the impressions to be made, I provide an attachment, consisting of a plate 32 having sleeves 33—33 in which rods 34—34 are rigidly mounted. The plate 32 has depending end flanges 35—35 which are adapted to enter pairs of slots 25—25; said flanges have notches 36 adapted to fit over the rod 27, and also rear notches 37 which engage the plate 24 at the rear ends of the slots 25. When the plate 32 is thus mounted with the notches 36 resting on the rod 27, and the rear notches 37 engaging the plate 24, the rods 34—34 will be suspended forwardly over the platen 21. 110

Slidably mounted on the rods 34—34 are sleeves 38—38 which carry a plate 39, said plate thus being mounted in slidable adjustment on the rods 34—34; set screws 40—40 secure such adjustment. 5 The plate 39 is provided with three slots 41, 42 and 43, each of which is provided with an opening 44 to the edge of the plate. Adapted to be mounted in the slots 41, 42 and 43, or either or any number of said slots, are bolts 45, the heads 10 of which engage the under side of the plate at the sides of the slots. Rotatably mounted on each of the bolts 45 is a lug 46 on which a finger 47 is pivotally secured. Wing nuts 48 thread on to the bolts 45 and secure the lugs in desired 15 adjustment. Adapted to be mounted slidably on either of the rods 34 is a collar 49 which is secured in desired adjustment on the rod by means of a set screw 50. Rotatably mounted on the collar 49 is a lug 51 which is secured in desired 20 adjustment by means of a set screw 52. Pivotally secured to the free end of the lug 51 is a finger 53, similar to the fingers 47.

In Figure 5 I have shown a modified form of the plate 24 and the lugs carried by the stamp 28, 25 in which form said lugs are provided with terminal balls 54 which are adapted to enter into depressions 55 of the plate 24.

The manner of using the device as above described is as follows:

30 The operator places the card or sheet to be printed on the platen 21 with its edges abutting the flanges 18 and 19 of the plate 1 on which the platen is then moved into approximate relation with the plate 24, and a pair of its slots 25 or 35 depressions 55. The stamp is then placed with its lugs 30 in said slots 25 and with the notches 31 in engagement with the rod 27 or with the balls 54 in depressions 55. The stamp is then rocked forwardly to make an impression. If the 40 location of the impression on the card or sheet is not accurate with respect to the side or upper or lower margins the platen may be moved laterally by sliding the collars 13 on the rod 10 and forwardly or rearwardly moving the entire assembly on the rods 8—8. If only a fair degree 45 of accuracy as to margin is to be attained, it may be that such adjustment will be entirely satisfactory for allocating the platen and sheet with respect to the stamp guided in the slots 25 and by the rod 27. Where, however, extreme 50 accuracy is desired, which will always be the case where impressions are to be made from a plurality of stencils, as in two or more color work, the proper adjustments are attained by means 55 of the fingers 47—47 and 53. This adjustment is effected by placing the plate 32 with its flanges 35 in the desired slots, as above described, so as to suspend the plate 39 and the arms 34—34 over the platen and card. When so suspended, 60 the fingers 47—47 and 53 are set so as to point directly to certain controlling portions of the impression previously made, as for instance, marginal and line portions. When so set, the platen with the sheet thereon is adjusted as above set 65 forth with reference to the fingers 47—47 and 53. By this means, as will be seen, the location of the impression on the card may be predetermined with extreme accuracy, and it thus becomes a simple matter to make subsequent impressions merely by repeated operations of the duplicating stamp. For the sake of making such accurate adjustment, it will be understood that it may not at all times be necessary to use as many as three fingers, one or two being sufficient, the desired number and placement of the

fingers in the slots of plate 59 and on the rods 34—34 being determined in each case with respect to the work in hand.

Having thus fully described my invention, what I claim as new and desire to secure by Letters Patent is:

1. A device of the character specified comprising in combination with a duplicating stamp, a plate having a depending flange adapted to serve as an abutment for a sheet to be stamped a resilient mount for said plate, a second plate, means whereby said plates may be relatively adjusted, and cooperative means carried by said stamp and second plate for allocating said stamp with reference to a sheet positioned by said first plate. 90

2. A device of the character specified comprising in combination with a duplicating stamp, a plate having a depending flange adapted to serve as an abutment for a sheet to be stamped a resilient mount for said plate, a second plate, means whereby said plates may be relatively adjusted, a lug on said stamp, and means carried by said second plate and arranged to cooperate with said lug for allocating said stamp with reference to a sheet positioned by said first plate. 95

3. A device of the character specified comprising in combination with a duplicating stamp, a plate having a depending flange adapted to serve as an abutment for a sheet to be stamped a resilient mount for said plate, a second plate, means whereby said plates may be relatively adjusted, means for rigidly securing said adjustment, and cooperative means carried by said stamp and second plate for allocating said stamp with reference to a sheet to be positioned by said first plate. 100

4. A device of the character specified comprising in combination with a duplicating stamp, a plate having a depending flange adapted to serve as an abutment for a sheet to be stamped a resilient mount for said plate, a second plate, means whereby said plates may be relatively adjusted, means for rigidly securing said adjustment, a lug on said stamp, and means carried by said second plate and arranged to cooperate with said lug for allocating said stamp with reference to a sheet 115 positioned by said first plate.

5. A device of the character specified comprising in combination with a duplicating stamp, a plate having a depending flange adapted to serve as an abutment for a sheet to be stamped, a second plate, means whereby said plates may be relatively adjusted, a plurality of lugs on said stamp, balls carried on the ends of said lugs, and depressions in said second plate arranged to receive said balls for allocating said stamp with reference to 120 a sheet positioned by said first plate.

6. A device of the character specified comprising in combination with a duplicating stamp, a plate having a depending flange adapted to serve as an abutment for a sheet to be stamped, a second 125 plate, means whereby said plates may be relatively adjusted, means for rigidly securing said adjustment, a plurality of lugs on said stamp, balls carried on the ends of said lugs, and depressions in said second plate arranged to receive said balls for allocating said stamp with reference to 130 a sheet positioned by said first plate.

7. A device of the character specified comprising in combination with a duplicating stamp, a plate having a depending flange adapted to serve 135 as an abutment for a sheet to be stamped, a second plate, means whereby said plates may be relatively adjusted, cooperative means carried by said stamp and second plate for allocating said stamp with reference to a sheet positioned by said first plate. 140

- plate, a third plate, means for securing said third plate to said second plate, and adjustable fingers carried by said third plate and adapted to be adjusted with reference to said sheet whereby said first plate may be adjusted in relation to said second plate for allocating the impression of said stamp on said sheet.
8. A device of the character specified comprising in combination with a duplicating stamp, a plate having a depending flange adapted to serve as an abutment for a sheet to be stamped, a second plate, means whereby said plates may be relatively adjusted, cooperative means carried by said stamp and second plate for allocating said stamp with reference to a sheet positioned by said first plate, a third plate, means for securing said third plate to said second plate, rods carried by said third plate, fingers adjustably mounted on said rods and third plate and adapted to be adjusted with reference to said sheet whereby said first plate may be adjusted in relation to said second plate for allocating the impression of said stamp on said sheet.
9. A device of the character specified comprising in combination with a duplicating stamp, a plate having a depending flange adapted to serve as an abutment for a sheet to be stamped, a second plate, means whereby said plates may be relatively adjusted, a lug on said stamp, means carried by said second plate and arranged to cooperate with said lug for allocating said stamp with reference to a sheet positioned by said first plate, a third plate, means for securing said third plate to said second plate, and adjustable fingers carried by said third plate and adapted to be adjusted with reference to said sheet, whereby said first plate may be adjusted in relation to said second plate for allocating the impression of said stamp on said sheet.
10. A device of the character specified comprising in combination with a duplicating stamp, a plate having a depending flange adapted to serve as an abutment for a sheet to be stamped, a second plate, means whereby said plates may be relatively adjusted, a lug on said stamp, means carried by said second plate and arranged to cooperate with said lug for allocating said stamp with reference to a sheet positioned by said first plate, a third plate, means for securing said third plate to said second plate, and adjustable fingers carried by said third plate and adapted to be adjusted with reference to said sheet, whereby said first plate may be adjusted in relation to said second plate for allocating the impression of said stamp on said sheet.
11. A device of the character specified comprising in combination with a duplicating stamp, a plate having a depending flange adapted to serve as an abutment for a sheet to be stamped, a second plate, means whereby said plates may be relatively adjusted, a plurality of lugs on said stamp, balls carried on the ends of said lugs, depressions in said second plate arranged to receive said balls for allocating said stamp with reference to a sheet positioned by said first plate, a third plate, means for securing said third plate to said second plate, and adjustably mounted fingers carried by said third plate and adapted to be adjusted with reference to said sheet, whereby said first plate may be adjusted in relation to said second plate for allocating the impression of said stamp on said sheet.
12. A device of the character specified comprising in combination with a duplicating stamp, a plate having a depending flange adapted to serve as an abutment for a sheet to be stamped, a second plate, means whereby said plates may be relatively adjusted, a plurality of lugs on said stamp, balls carried on the ends of said lugs, depressions in said second plate arranged to receive said balls for allocating said stamp with reference to a sheet positioned by said first plate, rods carried by said third plate, and fingers adjustably mounted on said rods and third plate and adapted to be adjusted with reference to said sheet, whereby said first plate may be adjusted in relation to said second plate for allocating the impression of said stamp on said sheet.
